US00D966334S

(12) **United States Design Patent** (10) Patent No.: **US D966,334 S**
(45) Date of Patent: ** *Oct. 11, 2022

(54) **DISPLAY PANEL PORTION WITH A COMPUTER ICON**

(71) Applicant: **Magic Leap, Inc.**, Plantation, FL (US)

(72) Inventors: **Lorena Pazmino**, Wilton Manors, FL (US); **Sarah Machicado**, Miami, FL (US); **Michael A. Pinkin**, Baltimore, MD (US); **Andrea Isabel Montoya**, Plantation, FL (US)

(73) Assignee: **Magic Leap, Inc.**, Plantation, FL (US)

(*) Notice: This patent is subject to a terminal disclaimer.

(**) Term: **15 Years**

(21) Appl. No.: **29/789,442**

(22) Filed: **Sep. 23, 2021**

Related U.S. Application Data

(63) Continuation of application No. 29/721,118, filed on Jan. 17, 2020, now Pat. No. Des. 933,706.

(57) **CLAIM**

The ornamental design for a display panel portion with a computer icon, substantially as shown and described.

DESCRIPTION

The single FIGURE is a front view of a display panel portion with a computer icon, showing our new design.

The broken lines showing a display panel portion and portions of the computer icon form no part of the claimed design.

1 Claim, 1 Drawing Sheet
